UNITED STATES PATENT OFFICE.

HERMAN COOK, OF ABERDEEN, SOUTH DAKOTA.

THRESHING-MACHINE.

No. 827,851.

Specification of Letters Patent.

Patented Aug. 7, 1906.

Application filed October 31, 1905. Serial No. 285,317.

To all whom it may concern:

Be it known that I, HERMAN COOK, a citizen of the United States, residing at Aberdeen, in the county of Brown and State of South Dakota, have invented a new and useful Threshing-Machine, of which the following is a specification.

This invention relates to threshing-machines; and the principal object of the invention is to present an improved structure containing in a single organized machine not only the threshing and separating mechanism of an ordinary threshing-machine, but also the motor means required to move the machine from one place to another and for running or driving the operative parts of the threshing-machine when the latter is set up in position for operation.

Further objects of the invention are to simplify and improve the construction and operation of this class of devices and to so combine and arrange the working parts of the device that the operative parts of the threshing-machine may be started in operation absolutely without loss of time after the machine has been guided to and placed in the proper position for operation.

With these and other ends in view, which will readily appear as the nature of the invention is better understood, the invention consists in the improved construction and novel arrangement and combination of parts, which will be hereinafter fully described, and particularly pointed out in the claim.

In the accompanying drawings has been illustrated a simple and preferred form of the invention, it being, however, understood that no limitation is necessarily made to the precise structural details therein exhibited, but that changes, alterations, and modifications within the scope of the invention may be made when desired.

In the drawings, Figure 1 is a side elevation of a threshing-machine constructed in accordance with the principles of the invention. Fig. 2 is a sectional plan view taken on the plane indicated by the line 2 2 in Fig. 1.

Corresponding parts in both figures are indicated throughout by similar characters of reference.

The invention has been illustrated as applied to a threshing-machine 1 of ordinary modern construction, of which the cylinder is designated 2, the separator-fan 3, and the stacker-fan 4. The threshing and separating mechanism has not been shown in detail,

as it does not form a part of the invention; but it may be constructed, and motion, so far as the separating mechanism is concerned, taken from the cylinder-shaft in the usual or any well-known and approved manner.

Upon the sills 5 at the forward part of the machine, beneath the casing of the latter, which has been shown as supported by uprights 6, is supported a motor M. This is preferably a gasoline-engine having four cylinders C C, the piston-rods of which, 7, are connected by pitmen 8 with cranks 9, disposed at right angles to each other upon the main driven shaft 10, which is supported in bearings upon the sills. Gibs or guideways 11 have been shown for the cross-heads 12 of the ends of the piston-rods. By using a plurality of cylinders, as herein described, the main driven shaft, which is provided with balance-wheels 13, can never stop on a dead-center. The liquid fuel is contained within a tank 14, supported within the casing of the machine, and is conveyed to the motor through a conducting-pipe 15.

Upon the main shaft 10 is mounted a slideable annularly-grooved friction-clutch member or collar 16, adapted to engage a friction-surface upon a bevel-pinion 17, which is in mesh with a bevel-pinion 18 upon one end of a suitably-supported shaft 19, the opposite end of which carries a bevel-pinion 20, meshing with a bevel-pinion 21 upon the shaft 22 of the threshing-cylinder 2, to which motion will thus be transmitted. The collar 16, which is splined upon the shaft 10, may be moved into or out of engagement with the pinion 17 by means of a shiftable-lever 23, connected by a link 24 with one arm of a bell-crank lever 25, the other arm of which is connected by a link 26 with an operating-lever 27, having a stop member adapted to engage a quadrant 28 for the purpose of retaining the parts in adjusted position.

Supported in suitable bearings at one side of the casing is a line-shaft 29, which is driven from the main shaft 10 by intermeshing bevel-gears 30 31, the latter of which may be locked upon the main shaft by a friction-clutch 31². The line-shaft 29 carries splined collars, as 32, having gear-wheels 33 for driving the separator-fan and the stacker-fan, the shafts of which are provided with pinions 34, and the tailings-elevator 35, the driving-shaft of which, 36, carries a pinion 37. The several collars 32 are annularly grooved and engaged by shiftable-levers 38,

all of which are connected with and simultaneously operable by a link-rod 39, connected with an operating-lever 40, having a stop member engaging a quadrant 41, whereby it may be secured in adjusted position. The line-shaft 29 also carries splined collars 42, having bevel-pinions 43, adapted to mesh with a bevel-pinion 44 upon a shaft 45, carrying a pinion 46, meshing with a spur-wheel 47 upon one of the hind wheels of the machine, which serves to propel the latter in a forward or rearward direction, according to which of the pinions 43 is in engagement with the pinion 44. The pinions 43 may also be retained at an intermediate position, so that both of said pinions will be out of mesh with the pinion 46, thus throwing the driving-gear out of operation. The collars 42 are annularly grooved, and they are in engagement with shipping-levers 48, whereby they may be adjusted to any one of the various positions indicated, the shipping-levers 48 being simultaneously operable by a link-rod 49, connected with an operating-lever 50, having a stop member adapted to engage a quadrant 51 for the purpose of retaining the parts operated by said lever in adjusted position.

A starting-lever 52, having a stop member 30 engaging a rack-segment 53, is provided, said starting-lever being connected by a link-rod 54 with the motor for the purpose of regulating the latter.

A steering-gear is provided, including a drum 55, upon which flexible members 56 are wound in opposite directions, said flexible members being connected with the front axle 57 near the ends of the latter. The drum 55 carries a worm-gear 58, meshing 40 with a worm 59 upon an upright shaft 60, located in convenient proximity to the driver's seat 61 and having a hand-wheel 62, whereby it may be conveniently manipulated.

From the foregoing description, taken in connection with the drawings hereto annexed, the operation and advantages of this invention may be readily understood. By

properly manipulating the several levers, all of which are located in a position conveniently accessible by the driver or operator, the motor may be started or stopped very swiftly and readily and motion may be imparted to the driving-gear for moving the machine forwardly or rearwardly, as may be required. As soon as the driving-gear has 55 been thrown out of operation the threshing and separating parts of the machine may be set in motion and driven at the required speed.

Where means have been shown for moving 60 gear wheels or pinions into and out of engagement with each other, ordinary well-known clutch means may be employed within the scope of the invention.

Having thus described the invention, what 65 is claimed is—

A threshing-machine having a running-gear and threshing parts, said running-gear and threshing parts being independent of each other operatively, a prime mover 10-75 located upon the thresher, a means in common to both the running-gear and threshing parts to transmit motion from the prime mover to the running-gear and threshing parts simultaneously or at different intervals, said 75 means consisting of a shaft operatively connected with the shaft of the prime mover and extending longitudinally and horizontally of the thresher and being capable of rotation in one direction only, means 80 simultaneously interrupting the motion from said shaft to the threshing parts, means for interrupting the motion from said shaft to the running-gear, the last-said means being capable of operation whereby motion is given 85 from said shaft to the running-gear in one direction or in the opposite direction.

In testimony that I claim the foregoing as my own I have hereto affixed my signature in the presence of two witnesses.

HERMAN COOK.
